United States Patent Office

Des. 179,098
Patented Oct. 30, 1956

179,098

PAPERWEIGHT

William R. Smith, Denver, Colo.

Application November 7, 1955, Serial No. 38,764

Term of patent 14 years

(Cl. D74—12)

330 1

330 2

Fig. 1 is a top view of a paperweight showing my new design; and

Fig. 2 is a side view thereof.

The bottom of the paperweight presents a similar appearance as the top disclosed in Fig. 1 and the undisclosed sides present a similar appearance as the side shown in Fig. 2.

I claim:

The ornamental design for a paperweight, as shown and described.
